UNITED STATES PATENT OFFICE.

EDWARD J. YARD AND WHITNEY E. DAVIS, OF KNOXVILLE, TENNESSEE.

SAND-TRAP.

1,147,587.

Specification of Letters Patent. Patented July 20, 1915.

Application filed March 22, 1915. Serial No. 16,196.

To all whom it may concern:

Be it known that we, EDWARD J. YARD and WHITNEY E. DAVIS, citizens of the United States, residing at Knoxville, in the county 5 of Knox, State of Tennessee, have invented a new and useful Sand-Trap, of which the following is a specification.

The present invention appertains to a sand trap for locomotives, and aims to provide a novel and improved trap device for 10 the rail sanders of locomotives, whereby the sand may be delivered from the sand box to the rail by means of a jet or stream of air, instead of by gravity.

15 It is the object of the invention to provide a sand trap of unique construction, and improved in its structural details, to enhance the utility and efficiency thereof, the trap including novel means for closing off the 20 sand duct or passage from the air duct or passage, when the device is idle, and in order that the sand may not flow backwardly into the air passage or duct.

Another specific object of the invention is 25 the provision of an air strainer or screen assembled with the trap in a unique manner, whereby it will effectively serve its purpose, and whereby the strainer or screen may be readily applied to and removed from 30 the trap.

A further object of the invention is the provision in a sand trap, of a valve mechanism between the air and sand passages or ducts, and of such construction as to be normally closed, and to be automatically opened 35 when the air or pressure fluid is turned on, in order that when the device is idle, the sand cannot flow backwardly into the air passage or duct.

40 With the foregoing and other objects in view which will appear as the description proceeds, the invention resides in the combination and arrangement of parts and in the details of construction hereinafter described and claimed, it being understood 45 that changes in the precise embodiment of the invention herein disclosed can be made within the scope of what is claimed without departing from the spirit of the invention.

50 The invention is illustrated in the accompanying drawing, wherein the figure is a median sectional view of the improved sand trap.

In carrying out the invention, there is

provided a body or casting 1, which is provided with a sand inlet port 2, a sand outlet port 3, an inverted V-shaped sand passage or duct 4 between the inlet and outlet ports and forming the trap, and holes 5 for the passage of bolts or other securing elements 55 therethrough to fasten the body to the sand box or other support, whereby the inlet port 2 is in communication with the sand box to receive the sand, and so that the sand will flow into the lower portion of the trap passage or duct 4. A cap 6 is also threaded upon the body 1 and serves as a closure for the upper or elbow portion of the passage or duct 4, the cap 6 having a babbitt liner 6^a in the line of the portion 4^a of the passage 70 or duct 4 which extends upwardly from the inlet port 2. The liner or insert 6^a is disposed above the downwardly projecting portion 4^b of the passage 4 and serves as a deflector for the sand, as will hereinafter more 75 fully appear. The body 1 is further provided with an inclined bore 7 extending from the lower end of the portion 4^a of the passage 4 in alinement or coaxial with the said portion 4^a. The bore 7 extends to the 80 exterior of the body 1 and is of smaller diameter than the portion 4^a of the passage 4. The body 1 has an annular air chamber or space 8 surrounding the bore 7 and located between the ends of the bore, and the 85 body is provided with a bore 9 extending upwardly from the chamber 8. The body is provided with a counter bore or enlarged socket 10 at the upper end of the bore or passage 9, and there is a tapered recess or 90 pocket 11 between the lower or restricted portion of the bore 9 and the counter bore 10. The pocket or recess 11 is tapered and has its lower end rounded, and the pocket or recess 11 is of smaller diameter than the 95 counter bore 10 and is of larger diameter than the bore 9. A bore 12 extends radially from the counter bore 10 and is preferably threaded for the reception of the air or pressure fluid pipe. A plug or cap 13 is 100 threaded into the counter bore 10 for normally closing the same, and is located above the bore 12 so as not to obstruct or close the same.

The bore 12, counter bore 10, pocket 11, 105 and bore 9 provide the air inlet passage or duct communicating with the lower or receiving end of the trap passage or duct 4

adjacent the sand inlet 2, and this air passage or duct is provided with a strainer for straining the air. The strainer embodies a ring 14 seated upon the shoulder or ledge 15 formed between the counter bore 10 and pocket 11 and a screen 16 has its edge secured to the ring 14 and is of a contour to fit snugly within the pocket 11. Thus, the air in flowing into the trap passes through the screen 16, for straining the air, and to prevent particles being carried beyond the strainer, which would be liable to render the device inoperative. The strainer may be readily inserted when the plug 13 is removed, and when the plug is removed, the strainer when in place can be readily withdrawn out of the counter bore 10. The plug 13 is provided with inwardly projecting pins or fingers 17 which contact with the ring 14 to hold the strainer seated when the parts are in place.

An automatic air valve is provided between the sand passage or duct 4 and the air passage or duct, and to this end a tubular valve casing or sleeve 18 is threaded or otherwise secured within the bore 7 so as to be in alinement or coaxial with the portion 4^a of the sand passage 4. The tubular valve casing 18 is preferably threaded into the bore 7 from within the passage 4, and the inner end of the casing 18 is provided with an enlargement or head 19 to limit the outward movement of the casing 18, and to provide a means for the engagement of a wrench whereby the casing may be readily threaded into and out of engagement with the trap body 1. It is evident, at this point, that the air valve is accessible through the portion 4^a of the passage 4 when the cap 6 is removed. The casing 18 is provided with inlet apertures 20 lying within the air chamber 8, whereby the air can enter the valve casing through the said apertures. A plug or member 21 is threaded or otherwise engaged into the inner or discharge end of the casing 18, and provides an outlet nozzle for the valve which is directed longitudinally into the portion 4^a of the passage 4 toward the deflector 6^a at the opposite end of the said portion 4^a. The outlet nozzle 21 has a restricted aperture or duct 22 extending therethrough, and is provided with a tapered valve seat 23 at the lower end of the plug or nozzle. A piston 24 is slidable within the casing 18 below the apertures 20 and is provided with an upwardly or inwardly projecting stem 25 having its free end portion reduced, as at 26, to enter the aperture 22 of the plug or nozzle 21, and the stem 25 is provided with a tapered portion 27 arranged to bear against the seat 23 for effectively closing the passage through the valve when the piston 24 is moved inwardly or upwardly adjacent the apertures 20.

As a means for normally seating the needle valve carried by the free end of the stem 25, there is provided a coiled wire expansion spring 28 disposed within the lower end 29 of the casing 18, and having its upper or inner end received by a socket or recess 30 formed in the piston 24. The downward movement of the piston 24 is limited by and the spring 28 is held within the portion 29 by means of an apertured plug 31 threaded or otherwise engaged into the lower end of the casing 18. The aperture of the plug or member 31 allows the air to flow inwardly and upwardly therethrough when the piston 24 is reciprocated. The spring 28 being disposed below or under the piston 24 serves to elevate or move the piston inwardly for seating the needle valve.

In operation, when the air is turned off, the reduced end portion or needle valve 26 will be seated against the plug or nozzle 21, under the influence of the spring 28 which forces the piston 24 inwardly or upwardly to a point adjacent but slightly below the apertures 20. This will prevent the sand within the trap from flowing backwardly into the air passage or duct, since it is especially desirable that the sand be not allowed to flow back through the nozzle 21, which would be liable to plug or clog up the nozzle. Now, when the air is turned on, it will flow through the air passage and into the casing 18 through the apertures 20, and the tendency for the pressure fluid to expand within the valve casing, will force the piston 24 downwardly or outwardly against the tension of the spring 28, and this will retract the needle valve from the nozzle 21, to allow the air to enter the sand passage 4. The air will be discharged in a jet or stream longitudinally through the portion 4^a of the passage 4 and against the deflector 6^a, and will draw the sand upwardly therewith so that it impinges against the deflector 6^a and then drops through the portion 4^b of the passage 4 and outlet 3 to the rail or rails. It will be understood that the inlet 2 of the body 1 may be connected to the sand box in any suitable manner, while the sand pipe leading to the rail or rails may be readily connected to the body 1 to communicate with the outlet 3. As soon as the air is shut off, the needle valve will immediately close automatically.

From the foregoing taken in connection with the drawing, it is believed that the advantages and attributes of the present invention will be obvious to those versed in the art, without further comment being necessary, it being noted that the present device is applicable for delivering the sand by air or pressure fluid, which is much more satisfactory than the delivery of the sand by gravitation.

Although the invention is illustrated and

embodied in a single sand trap, the structure may be duplicated to provide a double sand trap, and since this is a mere duplication, a detail description or illustration 5 thereof is not thought necessary.

The screen 16 will catch the particles carried with the air to the sand trap, and the plug or cap 13 may be removed from time to time, so that the strainer or screen can be 10 removed and emptied, which is a desirable feature of the invention.

Having thus described the invention, what is claimed as new is:—

1. In a device of the character described, a 15 body having a sand passage and an air passage leading thereto, said air passage including a bore extending from the sand passage and having a counter bore, there being a bore leading to said counter bore, a removable cap for closing said counter bore, and a strainer seated in said counter bore between said bores.

2. In a device of the character described, a body having a sand passage and an air 25 passage leading thereto, said air passage including a bore extending from the sand passage and having a counter bore, there being a bore leading to said counter bore, a removable cap for closing said counter bore, 30 and a strainer seated in said counter bore between said bores, the strainer and cap having coöperating means whereby the strainer is held in place by the cap.

3. In a device of the character described, a 35 body having a sand passage and an air passage extending thereto, said air passage including a bore having a counter bore, there being a pocket between said bore and counter bore and a second bore extending 40 from the counter bore, a detachable cap for closing said counter bore, and a ring seated in the counter bore and having a screen fitting in said pocket.

4. In a device of the character described, a 45 body having a sand passage and an air passage extending thereto, said air passage including a bore having a counter bore, there being a pocket between said bore and counter bore and a second bore extending from 50 the counter bore, a detachable cap for closing said counter bore, and a ring seated in the counter bore and having a screen fitting in said pocket, the ring and cap having co-

operating means whereby the ring is held in place by the cap. 55

5. In a device of the character described, a body having a sand passage and a pressure fluid passage extending thereto, the body having a nozzle for directing the pressure fluid into the sand passage, a piston mounted for 60 reciprocation within the body and having a needle valve coöperable with said nozzle for normally closing the same, the pressure fluid passage communicating with the space between said nozzle and piston, and a spring 65 for normally seating the needle valve.

6. In a device of the character described, a body having a sand passage and a pressure fluid passage, a tubular member secured within the body between the said passages 70 and having a nozzle directed into the sand passage and an inlet between its ends in communication with the pressure fluid passage, and a piston slidable within the tubular member and having a needle valve co- 75 operating with said nozzle to normally close the same, the piston being arranged to move away from said nozzle when the pressure fluid is admitted into said tubular member.

7. In a device of the character described, a body having a sand passage and a pressure fluid passage, a tubular member secured within said body between the said passages, a nozzle engaged within one end of said tubular member and projecting into the 80 sand passage, the tubular member having an inlet between its ends in communication with the pressure fluid passage, a piston slidable within the tubular member and having a needle valve coöperable with said 85 nozzle to normally close the same, the inlet of the tubular member being located between the nozzle and piston, and a coiled wire expansion spring disposed in the tubular member and bearing against the piston 90 to normally seat the needle valve against the nozzle.

In testimony that we claim the foregoing as our own, we have hereto affixed our signatures in the presence of two witnesses.
